United States Patent Office

Des. 182,209
Patented Feb. 25, 1958

182,209

FAN GUARD

Oscar M. Stanley, New York, N. Y., assignor to United Steel & Wire Company, Battle Creek, Mich., a corporation of Michigan

Application March 14, 1957, Serial No. 45,260

Term of patent 7 years

(Cl. D26—7)

I claim:

The ornamental design for a fan guard, as shown.
